UNITED STATES PATENT OFFICE.

AURELIUS S. HINDS, OF PORTLAND, MAINE.

CARTRIDGE SHOW-BOX.

SPECIFICATION forming part of Letters Patent No. 268,404, dated December 5, 1882.

Application filed July 31, 1882. (No model.)

To all whom it may concern:

Be it known that I, AURELIUS S. HINDS, of Portland, in the county of Cumberland and State of Maine, have invented a new and useful Improvement in Cartridge Show-Boxes; and I do hereby declare the same to be described in the following specification and represented in the accompanying drawings, of which—

Figure 1 is a top view. Fig. 2 is a longitudinal section taken on the line $x x$ of Fig. 1; Fig. 3, a transverse section of a body of one of my improved show-boxes, such section being on the line $z z$ of Fig. 1. Fig. 4 is a perspective view of it, showing its sustaining-leg.

It is intended for the holding and display of cartridges of medicaments, lozenges, or various other matters; and it consists of a shallow box-body provided with a cartridge-holding partition extending across it parallel to and a short distance above its bottom, and such partition having in it two or other suitable number of series of rectangular openings or slots, each of such slots being of a size to receive and fit closely to a cartridge, in order to firmly hold it in place in the box-body when the latter is inclined or set up on one end of it in a position to show or display the cartridges to advantage. Besides such partition, the box-body has a leg, C, pivoted to the under side of its bottom, the said leg when turned out into an acute angle with the body serving to sustain it when in an inclined position. The figures represent the box-body without a cover, it usually being supplied with one. In constructing

the partition I generally form in it two ranges 35 or series of the cartridge-receiving openings, with a wide space between such ranges to receive a printed statement or directions or explanations relating to the contents of the cartridges, their manner of use, &c., and I also 40 have a space in advance of the said two series of openings to receive another printed statement, all being as shown in the accompanying drawings, in which—

A denotes the box-body; B, the partition; C, 45 the leg; $a a$, the two series of rectangular openings for reception of cartridges b , the advertising-spaces between and that above the openings being shown at c and d . The bottom of the box-body I generally cover with red or some 50 other bright-colored paper or background, e , to attract attention when seen through any of the openings void of cartridges.

What I claim is—

A cartridge show-box consisting of a box, 55 body, A, having the inner surface of its bottom lined with paper e , and having in the box, over the lining and parallel therewith, a partition, B, provided with cartridge-holding openings a and with advertising-spaces $c d$, 60 the box being adapted to be supported on one end and by the leg C, and all being substantially as shown and described.

AURELIUS S. HINDS.
